UNITED STATES PATENT OFFICE

153,260

DESIGN FOR AN INDOOR-OUTDOOR
THERMOMETER

H. Brainard Brown, Rochester, N. Y., assignor to
Taylor Instrument Companies, Rochester, N. Y.,
a corporation of New York

Application November 7, 1947, Serial No. 142,396

Term of patent 14 years

(Cl. D52—7)

To all whom it may concern:

Be it known that I, H. Brainard Brown, a citizen of the United States of America, residing at Rochester, county of Monroe, State of New York, have invented a new, original, and ornamental Design for an Indoor-Outdoor Thermometer, of which the following is a specification, reference being had to the accompanying drawing, forming a part thereof, wherein:

Fig. 1 is a front elevation of an indoor-outdoor thermometer showing my new design;

Fig. 2 is a side view thereof;

Fig. 3 is a top plan view thereof.

I claim:
The ornamental design for an indoor-outdoor thermometer, as shown.

H. BRAINARD BROWN.
